UNITED STATES PATENT OFFICE.

CHARLES ADRIAN SAWYER, JR., OF NEWTON, MASSACHUSETTS.

SOLE-BLANK-CUTTING MACHINE WITH ADJUSTABLE KNIVES.

1,378,138.

Specification of Letters Patent.

Patented May 17, 1921.

Application filed April 28, 1920. Serial No. 377,321.

To all whom it may concern:

Be it known that I, CHARLES ADRIAN SAWYER, Jr., a citizen of the United States, and resident of Newton, in the county of 5 Middlesex and State of Massachusetts, have invented an Improvement in Sole-Blank-Cutting Machines with Adjustable Knives, of which the following description, in connection with the accompanying drawings, is 10 a specification, like letters on the drawings representing like parts.

My present invention relates to leather working machines, and more particularly to leather working machines for blanking-out 15 a plurality of shoe sole blanks simultaneously.

In my Patent No. 1,368,225, granted Feb. 8, 1921, I have described and claimed the novel features of construction and arrangement 20 of parts in a leather working machine known as a dinker. In such machine, I use an improved gang of cutters for blanking-out a plurality of shoe soles simultaneously, the cutters being rigidly mounted, and have 25 specifically claimed the same. In my further development of this type of machine, and appliances therefor, I have found that cut sole blanks, of practically all commercial sizes, have the same longitudinal outline; 30 that is, while the length of the sole blank and its width at various points along its length, will vary in accordance with the size of the sole blank, the longitudinal edges or contour of all sizes are practically identical. It is possible therefore, to blank out 35 soles of practically all commercial sizes by the use of but two cutters,—one right and one left hand.

In the use of my improved leather working machine, described and claimed in the application above referred to, I have had necessarily to form my gang cutters of a plurality of cutters bolted rigidly and non-adjustably in a cutter head, and have been 40 obliged to construct a separate gang of cutters for each size of sole blank to be cut. This course necessitated the investment of a large sum of money in fixtures and appliances, but one of which could be usefully 45 employed at any one time.

I have discovered that there is a point along the edge of a cut sole blank, regardless of the size of the blank, about which a cutter may rotate as on a pivot, to successively define shoe sole blanks of all 50 commercial sizes. Further, that the different

commercial sizes of shoe sole blanks can be obtained by use of the same set of cutters, provided the cutters can be moved laterally back and forth on the reciprocating 60 head or beam when one size or another is required by the operator. I am enabled therefore, to dispense with the multiplicity of gangs of cutters for the different sizes heretofore necessary, thereby reducing the 65 investment in tools and appliances to the lowest possible degree.

My improved adjustable gang cutters are adapted for use in dinker presses, particularly a dinker press such as that described 70 and claimed in my copending application, above referred to, and in this present application I have described and claimed the adjustable cutters in combination with such improved machine.

The object of my invention therefore, is an improved leather working machine and an adjustable gang cutter therefor, adapted to be adjusted to blank out shoe sole blanks 75 of all commercial sizes.

In the accompanying drawings,

Figure 1 is a front elevation of a dinker press embodying my invention,

Fig. 2 is a sectional side elevation on the line 2—2 of Fig. 1,

Fig. 3 is a plan view of my improved gang cutter, showing graphically the layout of different sizes of shoe sole blanks, and the manner of adjusting the individual cutters, and

Fig. 4 is a detail of the fastening means for the cutter.

Referring to the drawings, 10 designates side members or standards, spaced apart and comprising a frame. Near the top of the 95 standards 10, and in alignment with each other, are bearings 11 in which is rotatably mounted the main shaft 12. On one end of the shaft 12 is rotatably mounted a fly wheel 13, rotated usually by a belt (not 100 shown), a nut 14 being provided to hold the fly wheel 13 in position on the shaft. The lower ends of the side member 10 are connected to a cross bar 15 through which are threaded a plurality of adjusting bolts 105 16, engaging the lower face of a table 17, mounted for reciprocation in the frame. This table 17 is provided with ledges 18 and 19 on its front and rear sides respectively, to aid in positioning a block 20, of wood or other suitable material, a gib 21 and set screws 22 coöperating with the 110

ledges 18 and 19 for holding the block 20 rigidly in position.

Slidably mounted in the frame and above the block 20 is a cutter-head 23, to which a 5 gang plate 24 is secured by means of bolts 25. A shaft 26 mounted in the head 23 parallel to the main shaft 12, has attached thereto by set screws 27, the lower end of the connecting rods 28, the upper ends of 10 which are provided with bearings 29, engaging with eccentrics 30 keyed to the main shaft 12. Rotation of the shaft 12 will cause the reciprocating movement of the head 23 toward and from the block 20.

15 A clutch mechanism 31 on the main shaft 12 co-operates with the fly wheel to intermittently rotate the shaft 12 and reciprocate the head 23. An operating lever 32 pivotally mounted at its lower end to one of the 20 side members 10 of the frame, is controlled by a reciprocable safety plate 33 to operate the clutch mechanism. This clutch mechanism may be of any suitable type that will insure that a single complete revolution of 25 the main shaft 12 for one operating movement of the safety plate 33, but as the details of construction of such clutch is without the scope of the present invention, such details of construction will not be described.

30 The gang plate 24 is of suitable dimensions to permit the clamping thereon of a plurality of cutters 34 to blank out all the shoe blanks possible from a sheet of sole leather of predetermined size. On its front 35 and rear edges are T-slots 35, in which fit a plurality of square headed bolts 36 for adjustably mounting a plurality of spring-pressed stripper bars 37 in position to hold the sheet of leather in place and to strip the

40 sole blanks from the cutters 34 after the cutting operation. On the bottom face of the gang plate 24 are two T-slots 38 parallel to and spaced apart from each other and running lengthwise of the plate. The cutters 45 34 are constructed of a base plate 39 having a right-angled projection 40, of suitable contour, integral therewith, a flexible knife blade 41 being attached to the projection 40 by screws 42. The base plate 39 is provided with a hole at either end and spaced apart a distance equal to the distance between the T-slots 38. The holes in the base plate 39 are slightly larger than the diameter of the square headed bolts 43 which fit 50 into the T-slots 38 and are provided with nuts 44 for securely clamping the cutters 34 to the gang plate. The difference in diameter between the holes in the base plate 39 and bolts 43 allows sufficient angular movement of the cutters 34 with respect to the T-slots 38 for purposes of adjustment.

Referring specifically to Fig. 3, it will be noticed that a plurality of sole blanks 45, 46, 47, 48 and 49 are in engagement with the 60 cutter 34 at the left of said figure. Further,

that though the blanks of the different sized soles all have the same contour along their length, they are of different width, and that it is possible by maintaining the cutter at the left of the figure stationary, and rotating the other cutter 34 about the point 50 as a pivot, that the two cutters shown may be used to cut sole blanks of any desired size. At the right of Fig. 3, I have shown a plurality of lines 55, defining the longitudinal 70 edges of a plurality of different sizes of shoe sole blanks. These lines also represent the different positions of one of the cutters or knives 34 when in position to cut the different sizes of shoe sole blanks. I may 75 therefore, adjust the cutters to cut different sizes of shoe sole blanks by rotating the cutters about the pivot point 50, as shown in the center of Fig. 3, or may adjust such cutters by moving them laterally on the head 80 or beam 24, as shown at the right of Fig. 3. By first positioning the cutter at the left of Fig. 3, and then setting the remainder of the cutters by means of templets corresponding to the size of the blanks desired, I am 85 enabled to utilize a single gang of cutters on a single plate 24 for all sized blanks and to dispense with any appliances or attachments other than the plate and gang of cutters referred to, and while it may be advantageous 90 to provide one or more extra cutters 34 for emergencies, they are not essential.

While I have necessarily shown and described the preferred embodiment of my invention somewhat in detail, it is to be understood that I may vary the size, shape, and arrangement of parts constituting the same, within wide limits without departing from the spirit of the invention.

My invention is further described and defined in the form of claims as follows.

1. In a dinker press for shoe sole blanks, the combination of a frame, a reciprocating cutter head therein, there being longitudinally arranged parallel slots in said cutter head at each side thereof, a plurality of cutters defining the contour of the sides of a plurality of shoe sole blanks, and means, including said parallel slots for adjustably mounting said plurality of cutters in operative position on the head to define the contour of the sides of shoe sole blanks of different widths.

2. In a dinker press for shoe sole blanks, the combination of a frame, a reciprocating cutter head therein, there being longitudinally arranged parallel slots in said cutter head at each side thereof, a plurality of cutters defining the contour of the sides of a plurality of shoe sole blanks, and means to adjust predetermined cutters independently of the other cutters on the head, said adjusting means consisting in devices adapted to move one cutter toward and from its adjacent cutter.

3. In a dinker press for shoe sole blanks, the combination of a frame, a reciprocating cutter head therein, there being longitudinally arranged parallel slots in said cutter head at each side thereof, a plurality of cutters defining the contour of the sides of a plurality of shoe sole blanks, and means to adjust predetermined cutters independently

of the other cutters on the head, said adjusting means comprising cutter holding members adapted to adjust one cutter substantially toward and from its adjacent cutter and on a predetermined basis or base line. 10

In testimony whereof, I have signed my name to this specification.

CHARLES ADRIAN SAWYER, Jr.
